UNITED STATES PATENT OFFICE.

CARMAN M. SIMPSON, OF MILLVALE, PENNSYLVANIA.

RAIL.

No. 814,401.

Specification of Letters Patent.

Patented March 6, 1906.

Application filed November 24, 1905. Serial No. 288,866.

To all whom it may concern:

Be it known that I, CARMAN M. SIMPSON, a citizen of the United States of America, residing at Millvale, in the county of Allegheny and State of Pennsylvania, have invented certain new and useful Improvements in Rails, of which the following is a specification, reference being had therein to the accompanying drawings.

This invention relates to certain new and useful improvements in rails; and the primary object of the invention is to provide a novel form of rail which will be practically jointless. In this connection I have devised a rail particularly adapted for steam, electric, or tram railways, and in constructing my improved rail I form the same of a plurality of sections which are joined together to provide a continuous tread for rolling-stock that passes over the same. I have aimed to provide a rail the tread or head of which can be easily and quickly renewed at any desired time without removing the entire rail.

It is a well-known fact that considerable trouble is experienced in removing the ordinary spikes to renew a section of rail and also when a section has once been removed the same spike-holes of the ties cannot be again used. This permits water to enter the old holes in the tie and in the course of time renders the tie useless. By my improved jointless rail it will not be necessary to remove the spikes of a rail when it is desired to renew the wearing-surface or head of the rail, and in this manner a great saving is accomplished in the ties by increasing the longevity of the same. I have made allowances for the expansion and contraction of my improved rail, and the detail construction of the rail will be hereinafter more fully described and claimed.

Referring to the drawings accompanying this application, like numerals of reference designate corresponding parts throughout the several views, in which—

Figure 1 is a side elevation of a portion of a rail. Fig. 2 is a longitudinal sectional view of the same. Fig. 3 is a cross-sectional view taken on the line $\alpha\alpha$ of Fig. 1. Fig. 4 is a perspective view of a portion of a rail. Fig. 5 is a similar view of the tread-section of the rail, and Fig. 6 is a similar view of the base-section of the rail.

To put my invention into practice, I construct my improved rails of a plurality of sections, said sections being joined together at

places throughout the rail to form practically a jointless rail. In Fig. 1 of the drawings I have illustrated a portion of a rail wherein two tread-sections 1 1 are shown and three base-sections 2 2 2. The base-sections consist of base-flanges 3 3 and upwardly-extending parallel web-flanges 4 4, said flanges being provided with alining openings or slots 5 5 at their ends and 6 6 intermediate their ends.

The tread-sections 1 consist of a web portion 8 and a head or tread portion 9, said head or tread portion being similar to the ordinary type of rail at present used. The web portions of the sections 1 are provided with elongated openings or slots 10 10 adjacent to their ends and 11 11 intermediate their ends.

In assembling the sections of a rail the base-sections 2 2 2 are secured to the ties or foundation upon which the rail is to be laid, the sections being arranged end to end to form a continuous base-section. The head or tread sections are then placed in the base-sections, the web portions 8 of the sections 1 extending downwardly between the web-flanges 4 4 of the sections 2, the heads or treads 9 of the sections 1 resting upon the top edges of the web-flanges 4 4 of the sections 2. In placing the head or tread sections 1 1 in the base-sections 2 the sections 1 are arranged whereby their confronting ends will meet intermediate or centrally of the sections 2, thereby providing a firm and jointless base for the confronting ends of the sections 1 1 and a firm and solid head or tread for the confronting ends of the sections 2. It will thus be observed that the joints of the different sections throughout the rail are alternate, first one joint being formed in the sections 2 and then a joint in the sections 1.

To hold the sections 1 1 within the sections 2 2, nuts and bolts 14 are employed, and these bolts are placed in the openings of the base-sections 2 to engage in the openings or slots of the sections 1. The openings or slots 10 10 and 11 11 of the sections 1 are adapted to register with the openings 6 6 and 5 5 of the web-flanges 4 4 of the sections 2. In this manner each section 1 will be locked at two places to the sections 2, and it will be impossible for one section 1 to move independently of its adjoining sections or the base-section which supports said sections.

By forming a rail of a plurality of sections which are joined together in the manner just

described it is possible to renew the tread or head sections of the rail without removing the spikes that retain the base-sections in engagement with the ties or foundation upon which they are mounted, it only being necessary to remove the bolts and nuts 14 of the base-sections in order to remove any head or tread section 1. It is a well-known fact that the heads and treads of a rail become worn more rapidly than the base portions thereof. Therefore I have constructed my improved rail whereby a saving will be accomplished in using the base portions of a rail for possibly a plurality of head-sections, and in this connection I desire again to call attention to the fact that a great saving is incurred in the ties or foundations which support my improved rails.

I have allowed for the expansion and contraction of the sections of the rails by providing the elongated openings or slots 10, 10, 11, 11, 5, 5, and 6, 6 in the sections of the rail, these openings permitting of one section to expand and contract relative to its adjoining section.

It will be observed in Fig. 4 of the drawings that I have formed one of the head-sections integral with the base-section, thus providing a rail which can be easily used in connection with a switch or frog, the base portion of the rail only being dispensed with for a portion of its length in order that it may be secured to my improved rail-sections.

I do not care to confine myself to any specific means of securing the base-sections to the ties or foundations which support them, and such changes in the construction of my

improved rails as are permissible by the appended claims may be resorted to without departing from the spirit and scope of the invention.

What I claim, and desire to secure by Letters Patent, is—

1. A rail of the type described, consisting of a plurality of base-sections, a plurality of separate head or tread sections, certain of said base-sections being formed with vertical web-flanges having vertical openings formed therein, said tread-sections having web portions adapted to fit in the vertical openings in the base-sections, certain other of said base-sections being formed with integral heads for a portion of their length and said integral heads and the web-flanges of the last-named sections being prolonged beyond the base-flanges thereof and seating in the vertical openings in the web-flanges of the first-named base-sections.

2. A rail of the type described, consisting of a base-section, having a web-flange with a vertical opening therein, and a base-section having an integral web and tread portion, the web and tread portion of the last-named section being prolonged beyond the base-flanges thereof, and the said prolonged web portion seating in the vertical opening in the web-flange of the first-named section.

In testimony whereof I affix my signature in the presence of two witnesses.

CARMAN M. SIMPSON.
